UNITED STATES PATENT OFFICE.

VICTOR HUGO COCHRANE, OF TULSA, OKLAHOMA.

DAM CONSTRUCTION.

Application filed February 2, 1923. Serial No. 616,531.

To all whom it may concern:

Be it known that I, VICTOR H. COCHRANE, a citizen of the United States, residing at Tulsa, in the county of Tulsa and State of Oklahoma, have invented certain new and useful Improvements in Dam Constructions, of which the following is a specification.

This invention relates to improvements in dam constructions.

10 The primary object of this invention is the provision of an economical and aesthetic multiple arch dam construction, embodying features which render the same safe under varying conditions.

15 A further object of this invention is the provision of a multiple arch dam designed and constructed to remedy the defects generally found in arch dams, having particular regard to durability and flexibility of arrangement, and which may safely respond to various circumstances, such as shrinkage, elasticity of material, and changes in temperature without undue stress in parts or liability of fracture.

20 25 A further object of this invention is the provision of a simple and economical means of finishing the top of a multiple arch dam, which does away with the inherent weaknesses in ordinary arch dams and reduces the arch stresses and difficulties at this portion of the dam to a minimum.

30 35 A further object of this invention is the provision of a multiple arch dam, in which the shape, thickness, and other dimensions of the arches are particularly adapted for supporting the load placed thereon at various levels below the water surface.

40 45 A further object of this invention is the provision of a novel type of individually complete pier for multiple arch dams, which is stable in construction, and economical.

50 45 A further object of this invention is the provision of an arch for dam constructions, which embodies a flexible joint permitting of desired arch movements and deflections, incident to variable loads and other circumstances.

55 Other objects and advantages of this invention will be apparent during the course of the following detailed description.

In the accompanying drawings, forming a part of this specification, and wherein sim-

ilar reference characters designate corresponding parts throughout the several views.

55 Figure 1 is an elevation of the improved multiple arch dam, looking down stream.

Figure 2 is an elevation of a portion of the improved multiple arch dam, looking upstream.

60 Figure 3 is a transverse cross sectional view, taken substantially on the line 3—3 of Figure 4.

65 Figure 4 is a plan view of a portion of the improved multiple arch dam.

Figure 5 is a cross sectional view, taken substantially on the line 5—5 of Figure 4.

70 Figure 6 is a transverse cross sectional view, taken substantially on the line 6—6 of Figure 5.

75 Figure 7 is an enlarged transverse cross sectional view, taken substantially on the line 7—7 of Figure 5, showing certain features of arch design.

Figure 8 is an enlarged fragmentary cross sectional view, taken through a joint of an arch of the improved dam construction, showing the novel joint details.

80 Figure 9 is an enlarged fragmentary cross sectional view, taken substantially on the line 9—9 of Figure 8.

85 Figure 10 is an enlarged fragmentary cross sectional view, showing a modified type of joint for the arches of the improved dam.

Figure 11 is a fragmentary cross sectional view, through the type of dam illustrated in Figure 5, showing the addition of a parapet thereto.

90 Figure 12 is a fragmentary cross sectional view, showing a dam construction similar to that illustrated in Figure 5, with the addition of a wall thereto, to increase the height of the dam.

95 Figure 13 is an upstream fragmentary elevation of the improved dam construction, showing the provision of an overflow spillway in an arch thereof.

100 Figure 14 is a transverse cross sectional view, taken substantially on the line 14—14 of Figure 13.

Figure 15 is a fragmentary plan view of the improved dam construction illustrated in Figure 13.

Figure 16 is a transverse cross sectional

view, taken through an arch dam constructed in accordance with features of this invention and embodying a siphonic spillway.

In the drawings, wherein for the purpose 5 of illustration are shown certain embodiments of this invention, the letter A generally designates the improved dam construction, which preferably includes novel supporting piers B; novel arches C; and a novel 10 closure wall D.

In the construction of piers for multiple arch dams, the practice heretofore has been that of providing relatively narrow piers or buttresses which in most instances are 15 connected by tie rods or girders to prevent buckling or collapse of the same. This construction does not prove entirely satisfactory, on account of the liability of accidental failure of the same, so that in case one arch 20 and buttress should collapse, the entire series of arches will fail. To do away with this defect of construction, the improved pier B has been provided, which is simple and economical in design and may be made with 25 any desired degree of stability. The improved pier B is preferably of concrete or analogous cementitious material, and consists essentially of side walls 17, the rear or arch wall 18; the forward supporting wall 30 19; and transverse brace walls 20. The side walls 17, and the arch receiving wall 18, are of monolithic construction; the wall 18, of course, being inclined at any desired degree. To provide a very stable connection 35 of the top wall or slab 18 with the side walls 17, it is preferred to provide the fillets 22 at the juncture of said side walls with the wall 18, which face within the space provided intermediate the side walls 17. As the top 40 or arch wall 18 is subject to direct compression incident to the thrust of arches supported thereby, and also to flexure incident to its own weight and the superposed water load, it is preferred that the side walls 17 45 increase in thickness from the downstream end of the pier, toward the upstream end. In other words, as is illustrated in Figure 6 of the drawings, the side walls 17 increase uniformly in thickness from the downstream 50 supporting wall 19 toward the arch supporting wall 18. Any number of transverse walls 20 may be provided, which may be integrally formed at right angles to the side walls 17 and with the arch wall 18. The 55 downstream wall 19 of the pier B, may likewise be integral with the walls 17, as to seal the spaces intermediate the side walls 17. If desired, the side walls 17, and in fact, 60 any of the pier walls may be provided with enlarged footings 25 embedded in the bed rock.

It is obvious that the pier B may be given any desired degree of lateral stability, simply by increasing the transverse width and spacing of the walls 17. Thus, the pier can

be designed to carry the thrust of the unloaded arch on one side only, or can be made stable under full water load in case of the failure of an adjacent arch. Any degree or type of reinforcement may be provided. 70 This type of pier construction lends itself readily to dams which are curved in plan, and in this case it will be necessary to build the side walls 17 at intersecting planes instead of parallel relation, as is illustrated in 75 Figure 6 of the drawings.

Referring to the improved arch C, the same preferably includes the base portion 30; upper or major arch portion 31; said portions 30 and 31 being connected by an 80 improved joint construction 32, as to permit some degree of movement of the arch portion 31 with respect to the portion 30 or vice versa.

The arches of multiple arch dams are 85 especially susceptible of slight movements, which though small are essential, and it is extremely important that provision be made in the design and construction of the arches for such, in so far as the association of the 90 same with respect to piers and their foundations is concerned. Thus, an arch under load is shortened to a certain extent, owing to the elasticity of the masonry, causing the arch to deflect somewhat; this deflection being greatest at the crown and decreasing toward the ends. A similar deflection is produced by shrinkage of the concrete, and by shortening of the arch incident to fall in 95 temperature. On the other hand, increases of temperature or swelling of the concrete cause the arch to rise, so to speak, in the direction of the impounded water. In arch constructions heretofore provided no provision has been made at the base of the arch 100 as to permit sufficient arch action to prevent internal strains. It is well known that near the bottom of the arch, the proper degree of movement is prevented by the bed rock on 105 which the masonry is supported, so that proper deflection of the arch is almost entirely prevented at the base of the arch, and more or less impeded for considerable distance upwardly from the bed rock. As a consequence, the lower portion of the arch 110 acts like a cantilever beam in supporting the load which cannot be sustained by arch action. Unless this cantilever portion, so called, is heavily reinforced, and anchored to the bed rock, cracks develop on the upstream side of the arch. On the other hand, if the reinforcement and anchorage metal are sufficiently heavy to prevent cracking of the concrete, the masonry may be so highly stressed as to require thickening near the 115 bed rock level. This thickening in turn aggravates the original difficulty, since the cantilever is now stiffer and consequently sustains an augmented load. An important 120 object effected by the improved arch, which 125

utilizes the novel joint construction 32, is to insure the proper arch action down to a suitable or predetermined point, and below that a definitely determinable amount of cantilever action, requiring much less reinforcement and masonry than for the monolithic arch construction heretofore provided.

Referring to the improved joint 32, which is illustrated in the various views of the drawings, and in enlarged section in Figure 8, the same extends transversely across the arch C, intermediate the facing surfaces of the arch portions 30 and 31, and terminating at its ends in spaced relation adjacent the springing edges 35 of the arch. The plane of the joint 32 is substantially at right angles to the axis of the arch, and is not carried entirely across the arch, since there is very little, if any, movement which takes place adjacent the springing portions of the arch, so that the base and major portions 30 and 31 of the improved arch C may be constructed integrally outwardly from the ends of the joint 32 to the springing edges 35 of the arch.

Referring to the improved joint 32, as is illustrated in Figure 8 of the drawings, and according to the process of constructing the same, the base 30 is first built with suitable reinforcing metal 37 embedded therein, and the V-shaped metal diaphragm 38 is anchored at one leg 39 within the top surface of the base 30, between the extrados 40 and intrados 41 of the base arch portion 30, so that the other leg 43 extends upwardly above the top surface of the base 30, and is adapted for anchorage within the major arch portion 31, as will be subsequently set forth. It is to be noted that the legs 39 and 43 of the metal diaphragm 38 are in diverging relation toward the extrados of the arch C, and may be provided with suitable anchoring lugs, as is illustrated in the drawings. From the rear of the diaphragm 38 toward the intrados of the arch, the abutting surfaces of the arch portions 30 and 31 should be finished smooth, and if desired, these surfaces may be finished at a slight angle to the direction of motion of the arch A when deflecting, as is illustrated in Figure 8 of the drawings. These surfaces of the arch portions 30 and 31 are substantially intermediate the extrados and intrados of the arch, and between said surfaces asphalt or tar paper 45 is provided, as to effect a slip joint construction, preventing the concrete of the arch portions 30 and 31 from adhering to each other. During the construction of the arch joint both at the extrados and the intrados of the arch, recesses are provided in the top of the base 30. Prior to the pouring of the concrete for construction of the arch portion 31, a recess immediately at the rear of the diaphragm 38 is permanently filled with some water proofing ma-

terial, 47, as asphalt, and upon which the concrete for the arch portion 31 may be poured.

The recess at the extrados side of the arch and above the diaphragm 38 is preferably provided with a wooden or metal form, which can be removed when the arch portions 30 and 31 are set. The transverse strip of flexible waterproof sealing material 50 may then be poured in this recess, and which in depth extends from the extrados of the arch to the bottom of the diaphragm 38. This material 50 is, of course, placed before the water is permitted to rise to the level of the joint 32, and may be of any suitable material, such as asphalt. A recess 52 is exposed at the intrados of the arch, which may be of various shapes, and provided by collapsible forms intermediate the arch portions 30 and 31. This recess 52 is at the downstream side of the arch, and is left open until the arch has taken its full load and is under proper temperature conditions, and at which time the same may be filled with grout or concrete as to permanently seal the joint under predetermined conditions of stress. In cross section, the concrete 53 which provides the joint in the recess 52 may be T-shaped and suitably anchored by its head within said recess.

Referring to the modified form of joint 55, as illustrated in Figure 10 of the drawings, the V-shaped diaphragm 56 may be provided therein in manner similar to the diaphragm 38 above described. The slip joint material 57, analogous to the slip joint 45 provided in the preferred form A, may also be included as a part of the joint 55. The permanent flexible seal 58 may be disposed immediately at the rear of the diaphragm 56, and the waterproof seal of asphalt may be provided in exposed relation at the extrados of the arch in which the modified joint 55 is provided. At the downstream or intrados side of the arch embodying the modified joint 55, the wedge joint of concrete 60 may be provided after proper arch deflection.

Referring to the shape of the arch C, the thickness at the crown of the same increases substantially uniformly from the top of the arch to the base thereof. As the thrust or axial pressure on the arch, incident to the impounded water and arch loads does not vary greatly, at any cross section of the arch from the center to the springing ends thereof, if these loads were considered alone, the arch thickness at any cross section might be made uniform from the crown to the springing edges, and as is done in present practice. However, consideration of the effects of arch shortening, shrinkage, and temperature variations show that the arch should have a greater thickness at the ends or adjacent the springing edges than at the

central portion of the arch. It has been found that it is not necessary to thicken the arch from the central line thereof to predetermined points on each side thereof, near 5 the quarter points of the arch; and from which quarter points toward the springing edges of the arch, said arch may uniformly increase in thickness. As is illustrated in Figure 7, the extrados of the arch C is preferably formed on a single radius. The intrados of the arch from the central line of the arch to the points 65 on each side thereof, is struck from a single radius which is concentric with the radius forming the 10 extrados of the arch. From the points 65 to the springing edges 35 of the arch C, shorter radii are used, as to increase the thickness from said points 65 to the springing edges 15 of the arch. These radii upon which the arch C is formed are to be chosen so that the center line or axis of the arch at some section near the base coincides as nearly with the line of pressure as possible, incident to the arch and water loads. 20 Near the top of the arch, it is possible that there may be some eccentricity of pressure, but this will be of no consequence, in view of the fact that the minimum practical limiting thickness of the arch provides an excess of strength at this point. Since the intrados is of the same curvature from the top to the bottom of the arch, the same forms may be used throughout the arch 25 construction.

Referring to the improved closure wall D, provided in connection with the dam construction A, the same rests upon the arches C and piers B, and should be properly anchored thereto. This wall D is set in a plane substantially at right angles to the longitudinal axes of the inclined arches C, for several important reasons—first, so that the same will be parallel to other parts of the arch, such as the transverse joint 32, and 30 whereby the dam construction may be simplified and the stresses best distributed; second, an important feature of this wall is that the same resists the pressure of the water wholly, or in part, by the weight of the wall itself. As is illustrated in the drawings, the portion 70 of the wall D adjacent the piers B is of greatest height and thickness, and toward the crowns of the 35 arches C, said wall D decreases in height, so that the wall portion 72 at the crown of the arches is of least depth. This wall may be reinforced, to sustain the water pressure and its own weight, and may be reinforced longitudinally to prevent cracking under various temperature conditions.

At the top of the wall D, the horizontal foot way 73 may be provided across the dam A. If desired, a parapet 74 may be built upwardly from the top of the wall D in vertical manner, as is illustrated in Figure

11 of the drawings, upon which a roadway or footway may be provided, as desired. It is contemplated that the dam A may be increased in height, and as is illustrated in Figure 12 of the drawings, a portion 75 may be added to the wall D in a vertical plane either at the time of original building of the dam or at any subsequent period thereto.

In Figures 13, 14 and 15, an overflow type of the improved dam has been shown, at the 75 top of each arch C of which a spillway 79 is provided, as by breaking the continuity of the top wall E, so that at the crown portion of each arch C, said wall is removed. At the downstream side of the dam construction A, a basin or spilling pool 80 may be provided, for each arch C, which receives the water pouring through the spillway 79 of its adjacent arch, as to prevent the water from injuring the foundation parts of the 80 arch or dam construction.

As is illustrated in Figure 16, the improved dam is susceptible of having a siphonic spillway 85 provided therein. This spillway 85 is preferably formed in the 90 downstream wall 86, and the top wall F. The top portion 87 of the spillway 85 is provided with a bend which communicates with the upstream or impounded water beneath the depending portion 88 of the dam wall 95 D; said portion 88 having a transverse opening 89 therein communicating with the upper portion of the spillway 85, so that the siphon action may readily take place should the water impounded rise above the transverse opening 89. A shoulder 90 may be provided at the bottom of the spillway, in the downstream wall 86, which restricts the passageway of said spillway. Other features of the improved dam embodying the 100 siphonic spillway are substantially the same as above described.

From the foregoing description of this invention, it is apparent that a multiple arch dam has been provided, the various parts of which cooperate in overcoming defects which are inherent in present day practice of dam construction.

Various changes in the shape, size, and arrangement of parts may be made to the forms of the invention herein shown and described, without departing from the spirit of the same and the scope of the claims.

I claim:

1. An arch for dam constructions provided with a substantially transverse waterproof joint to permit portions on opposite sides of said joint to move relative to each other.
2. An arch for dam constructions substantially subdivided into a major upper portion and a base portion by a waterproof joint permitting relative movement of said arch portion.
3. An arch for dam constructions pro-

vided with a flexible joint extending substantially transversely through the crown portion thereof.

4. An arch for dam constructions provided with a flexible joint extending substantially transversely through the crown portion thereof, and subdividing said arch into an upper portion comprising the major portion of said arch, and a lower base portion.

5. An arch for dam constructions having a transverse flexible joint at right angles to the axis of the arch, the ends of said joint terminating short of the springing edges of the arch, whereby said arch is divided into portions on opposite sides of the joint capable of safe relative movement.

6. An arch for dam constructions providing a foundation portion, a concavo-convex arch portion, and a water proof joint connecting said arch and foundation portions to permit arch deflection.

7. An arch for dam constructions having a flexible waterproof joint extending transversely thereof inwardly from the extrados thereof to permit safe movement of the portions of the arch on opposite sides of said joint.

8. A retaining arch of cementitious material including a ground imbedded base portion, a major arch portion, and a joint intermediate the base and major arch portions which will permit safe deflection of the arch portion with respect to the ground embedded base portion.

9. In a device of the class described, the combination of a supporting base, an arch, and waterproof means intermediate the supporting base and arch permitting deflection or relative movement of the arch with respect to the supporting base.

10. An arch for dam constructions having a flexible joint thereacross consisting of a flexible material disposed inwardly of one side of the arch, and a non-flexible material disposed inwardly of the opposite side of the arch.

11. An arch for dam constructions having a flexible joint thereacross consisting of a flexible material disposed inwardly of one side of the arch, a non-flexible material disposed inwardly of the opposite side of the arch, and means providing a slip joint between the flexible and non-flexible materials of the joint.

12. An arch for dam constructions including a flexible joint extending thereacross consisting of a metal diaphragm anchored in said arch on opposite sides of said joint, a flexible material disposed inwardly of one side of the arch adjacent said diaphragm, and means providing a slip joint at the opposite side of said diaphragm from said flexible material.

13. In an arch for dam constructions the combination of a pair of arch portions separated by a joint, said joint including a V-shaped metal diaphragm anchored inwardly of the portions of the arch adjacent said joint, a flexible material extending inwardly of the extrados side of said arch at one side of said diaphragm, a cementitious non-flexible material anchored inwardly of the intrados side of said arch, and a strip of material providing a slip connection between the facing surfaces of the arch portions between the non-flexible material of the joint and said diaphragm.

14. A retaining arch comprising a base, an arch concavo-convex portion, and a joint intermediate the base and arch portions including a waterproof sealing material disposed inwardly of the convex side of the arch, a metal diaphragm, anchoring the base and arch portions, and a permanent sealing material intermediate the convex and concaved sides of the arch.

15. That method of constructing arches which consists in pouring a base, providing a water proof joint construction upon said base, pouring an arch portion, and upon settling of the arch portion with respect to said base at the joint of said base and arch portions providing a permanent seal.

16. That method of constructing arches for dams which consists in the pouring of a base, providing a slip joint on said base, pouring an arch portion on said slip joint, and upon predetermined settling of the arch portion with respect to the base permanently sealing the joint at the base and arch portions.

17. That method of constructing arches for dams which consists in separately pouring base and arch portions with a slip joint therebetween and recesses in the intrados and extrados sides of the juncture thereof, sealing the extrados side of the arch with a waterproof flexible material, and upon predetermined positioning of said arch portion with respect to said base permanently disposing a cementitious seal in the recess at the intrados side of said arch.

18. That method of constructing arches for multiple arch dams which consists in pouring the base portion and major arch portions of said arch so as to leave recesses inwardly of the intrados and extrados thereof at the juncture of said base and major arch portions, said recesses extending substantially transversely of the arch, sealing the extrados recess with flexible waterproof material, subjecting the arch to its load and at a predetermined time sealing the intrados recess with a permanent cementitious material.

19. In an arch dam, the combination of an inclined arch, and a cantilever wall supported by said dam at the top of said arch

extending at the upstream side of the arch and at substantially right angles to the axis of the arch.

20. A multiple arch dam comprising piers, arches supported by the piers on inclined axes, and a cantilever wall supported at the top of the dam by said arches and piers and sloping upstream at right angles to the axes of the arches.

10 21. A multiple arch dam comprising piers, arches, and walls anchored to said piers and arches at the top of said dam extending outwardly of the arches and being of least depth at the crown of said arches.

15 22. A multiple arch dam comprising a plurality of arches having the convex sides thereof facing upstream, and a cantilever wall carried by the arches and extending substantially at right angles to the axes of the arches at the tops thereof toward the upstream sides.

25 23. A multiple arch dam comprising a plurality of arches having the convex sides thereof facing upstream, and a wall extending substantially at right angles to the axes of the arches at the tops thereof toward the upstream sides, said wall having a horizontal top edge at its free end.

30 24. A dam construction comprising a plurality of hollow piers each including arch supporting walls, a plurality of arches spanning said piers with the springing edges thereof resting upon said supporting walls, and a top wall for said dam connected with said arches and side walls and extending toward the upstream side thereof at right angles to the axes of the said arches.

35 25. A dam construction comprising a pier having spaced side walls, and an inclined wall supported by said side walls, and arches supported by said piers, each of said

arches being transversely jointed intermediate the upper and lower portions thereof to permit relative movement of said portions on opposite sides of said joint.

45

26. In a multiple arch dam the combination of a pair of adjacent arches having convex sides facing upstream, said convex sides being arranged throughout the height of said arches to the top thereof, and a wall 50 connected with the top portions of said arches extending at an oblique angle to the axes of said arches and sloping towards the upstream side of said arches, said wall being arranged between the crowns of said arches so as to be shallowest at the crowns and deepest adjacent the springing edges of said arches.

27. In a multiple arch dam the combination of a pair of adjacent arches having convex sides facing upstream, said convex sides being arranged throughout the height of said arches to the top thereof, a wall connected with the top portions of said arches extending at an oblique angle to the axes of 60 said arches and extending towards the upstream side of said arches, said wall being arranged between the crowns of said arches so as to be shallowest at the crowns and deepest adjacent the springing edges of 65 said arches, and a buttress connected at the springing edges of said arches and extending outwardly from the downstream side of said arches.

28. In an arch dam the combination of an 70 arch wall, and an extension formed at the upper portion of the arch wall providing a surface obliquely arranged with respect to the axis of the arch in overhanging relation with the upstream side of said arch.

VICTOR HUGO COCHRANE.
